(57) CLAIM

The ornamental design for a surface configuration of a vehicle and/or toy body, as shown and described.

DESCRIPTION

This application is related to co-pending application Ser. No. 29/137,721, of the inventors, filed Feb. 28, 2001 and entitled "Surface Configuration of a Vehicle and/or Toy."

FIG. 1 is a left, front perspective view of a first embodiment of a surface configuration of a vehicle and/or toy body according to our novel design, the right, front perspective view being mirror symmetrical;

FIG. 2 is a front view of the first embodiment of the surface configuration of a vehicle and/or toy body according to our novel design;

FIG. 3 is a left side view of the first embodiment of the surface configuration of a vehicle and/or toy body according to our novel design, the right side view being mirror symmetrical;

FIG. 4 is a left, rear perspective view of the first embodiment of the surface configuration of a vehicle and/or toy body according to our novel design, the right, rear perspective view being mirror symmetrical;

FIG. 5 is a rear view of the first embodiment of the surface configuration of a vehicle and/or toy body according to our novel design;

FIG. 6 is a top view of the first embodiment of the surface configuration of a vehicle and/or toy body according to our novel design;

FIG. 7 is a left, front perspective view of a second embodiment of the surface configuration of a vehicle and/or toy body according to our novel design, the right, front perspective view being mirror symmetrical;

FIG. 8 is a front view of the second embodiment of the surface configuration of a vehicle and/or toy body according to our novel design;

FIG. 9 is a left side view of the second embodiment of the surface configuration of a vehicle and/or toy body according to our novel design, the right side being mirror symmetrical;

FIG. 10 is a left, rear perspective view of the second embodiment of the surface configuration of a vehicle and/or toy body according to our novel design, the right, rear perspective view being mirror symmetrical;

FIG. 11 is a rear view of the second embodiment of the surface configuration of a vehicle and/or toy body according to our novel design; and,

FIG. 12 is a top view of the second embodiment of the surface configuration of a vehicle and/or toy body according to our novel design.

The broken lines included depict environment and are not part of the claimed design.
